DISPLAY STAND FOR SHOE ADVERTISING CARDS OR THE LIKE

Zvi Cohen, 57 Meetinghouse Road, Bedford, N.H.

Filed Dec. 17, 1959, Ser. No. 58,697

Term of patent 14 years

(Cl. D80—9)

FIG. 2

FIG. 1 is a front perspective view taken from the top of a display stand for shoe advertising cards or the like embodying my new design, the rear of the upright column being substantially plain; and

FIG. 2 is a right side elevational view thereof.

I claim:

The ornamental design for a display stand for shoe advertising cards or the like, substantially as shown and described.
